Inventor:
James Hirst
by his attorney, Linley May
Attyo.

UNITED STATES PATENT OFFICE.

JAMES HIRST, OF MELROSE, MASSACHUSETTS.

TAP WRENCH AND DIESTOCK.

Application filed April 17, 1922. Serial No. 554,241.

To all whom it may concern:

Be it known that I, JAMES HIRST, a citizen of the United States, residing at Melrose, in the county of Middlesex and State 5 of Massachusetts, have invented new and useful Improvements in Tap Wrenches and Diestocks, of which the following is a specification.

The object of this invention is to provide 10 a stock or holder adapted to securely confine and operate a pair of jaws which may be formed either to cut male screw threads, or to engage and rotate a tap, and permit the quick and convenient application and removal of the jaws and the substitution of others therefor.

The invention is embodied in the improvements which I will now proceed to describe and claim.

20 Of the accompanying drawings forming a part of this specification—

Figure 1 is a side view of a tool embodying the invention, provided with jaws formed as male screw-thread cutting dies.

25 Figure 2 is an edge view of the same, on a larger scale.

Figure 3 is a section on line 3—3 of Figure 2.

Figure 4 is a section on line 4—4 of Figure 3.

Figure 5 is a view similar to Figure 4, showing the jaw-securing bars displaced to release the dies.

Figure 6 is a perspective view of the stock 35 or holder, the dies, the die-securing bars, and the handles being removed.

Figure 7 is a side view of a pair of jaws, adapted to engage a tap.

The same reference characters indicate 40 the same parts in all of the figures.

The body of my improved stock or holder is composed of duplicate side portions 12, 12, and end portions 13 and 14, said portions bounding an opening 15, adapted to receive

45 a pair of jaws 16. The jaws may have acting portions 17, adapted to cut male screw threads on a bolt or rod, or may have acting portions 18, as shown by Figure 7, adapted to engage a tap. The side portions

50 12 are provided with slots 19, communicating with the opening 15, said slots having extensions 19^a, extending through the end portion 14, and along the periphery of a boss 20, formed on said end portion.

55 Connected by pivots 21 with the side portions 12, at one end of the holder, are two

jaw-engaging bars or tongues 22, having their free ends reduced in width and provided with ears 23, adapted to enter the portions of the slot extensions 19^a that are 60 formed in the boss 20. The jaws 16 are provided, in opposite edges, with grooves 24 which receive the inner edges of the tongues 22, when the tongues are in their operative positions shown by full lines in Figure 3. 65

The engagement of the tongues with the jaw grooves confines the jaws against sidewise displacement, and permits endwise movement of the jaws in the opening 15.

I provide means for releasably confining 70 the tongues 22 in their operative positions, said means being preferably embodied in a tubular flange 26, formed on a handle 27. Said handle is provided with a screw-threaded shank 28, engaged with a tapped 75 orifice in the boss 20, as shown by Figure 3. The ears 23 are flush with the boss 20, when the tongues are in their operative positions, and the arrangement is such that when the shank 28 is screwed inward, the flange 26 80 simultaneously overlaps and engages the ears 23, and constitutes a keeper confining the tongues in engagement with the jaws. When the shank 28 is screwed outward, the keeper simultaneously releases the ears 23, 85 so that the tongues may be swung outward, as indicated by Figure 5, and by dotted lines in Figure 3, to release the jaws and permit their sidewise removal.

To exert clamping pressure on the jaws 90 when they are confined by the tongues, I provide a handle 29, having a screw-threaded shank 30, engaged with a tapped orifice in a boss 31, formed on the end portion 13. The shank 30 projects into the opening 15, 95 and abuts against one edge of one of the jaws to press the same toward the other jaw.

The handles 27 and 29 project in opposite directions from the body, and enable the operator to turn the body as required, in causing the operation of the jaws. The handle 29 is preferably provided with a tubular flange 32, in sliding contact with the boss 31. The keeper flange 26 similarly contacts with the boss 20. The said flanges and bosses, 100 therefore, partially support the strain exerted on the handles, so that such strain is not sustained entirely by the shanks 28 and 30.

I claim:

1. A stock or holder of the character stated, comprising a body composed of side

and end portions bounding an opening formed to receive a pair of jaws, the side portions being provided with slots communicating with said opening, and having 5 extensions formed in one of the end portions, a pair of die-engaging tongues pivoted to the side portions at one end of the body, and having ears at their free ends, formed to occupy the slot and a keeper movably 10 engaged with said end portion and adapted to simultaneously engage said tongues and hold the same in position to engage grooves in a pair of jaws inserted in said opening, and to simultaneously release the tongues 15 and permit the same to be swung outward from the holder.

2. A stock or holder of the character stated, comprising a body composed of side and end portions bounding an opening 20 formed to receive a pair of jaws, the side portions being provided with slots communicating with said opening, and having extensions formed in one of the end portions, a pair of die-engaging tongues pivoted 25 to the side portions at one end of the body, and having ears at their free ends, formed to occupy the slot extensions, one end portion of the body being provided with a boss containing portions of said slot extensions, 30 a handle having a screw-threaded shank engaged with a tapped orifice in said boss, and a keeper movable by rotation of the handle to engage and release the tongue

ears, the tongues being adapted to be swung outward from the holder when said ears 35 are released.

3. A stock or holder of the character stated, comprising a body composed of side and end portions bounding an opening 40 formed to receive a pair of jaws, the side portions being provided with slots communicating with said opening, and having extensions formed in one of the end portions, a pair of die-engaging tongues pivoted 45 at the side portions at one end of the body, and having ears at their free ends, formed to occupy the slot extensions, the end portions of the holder being provided with bosses, one of which contains portions of 50 said slot extensions, said bosses being provided with tapped orifices, and a pair of handles having screw-threaded shanks engaged with said orifices, and tubular flanges in sliding contact with the bosses, one of 55 said flanges constituting a keeper, adapted to engage and release the tongue ears, the shank of the other handle being adapted to exert clamping pressure on the dies, said 60 handles being releasably secured in their operative positions by the engagement of the screw-threaded shanks with the tapped orifices of said bosses.

In testimony whereof I have affixed my signature.

JAMES HIRST.
